UNITED STATES PATENT OFFICE.

VINCENT G. APPLE, OF DAYTON, OHIO.

METHOD OF CONSTRUCTING ARMATURES FOR DYNAMO-ELECTRIC MACHINES.

Application filed September 15, 1919. Serial No. 324,020.

To all whom it may concern:

Be it known that I, VINCENT G. APPLE, a citizen of the United States, residing at Dayton, in the county of Montgomery and State 5 of Ohio, have invented certain new and useful Improvements in Methods of Constructing Armatures for Dynamo-Electric Machines, of which the following is a specification.

10 This invention relates to a method of constructing armatures for dynamo electric machines.

One of the objects of the invention is to improve armatures for dynamo electric machines by entirely enclosing the windings of 15 the armature in a relatively refractory insulating armor.

Another object is to provide a method of procedure, whereby the windings are saturated with a condensation product and while in a plastic state are reformed by pressure and preliminarily hardened by application of heat. Subsequently all of the conductors of the armature are encased in an insulating 25 covering or armor, preferably composed of condensation product and which is subjected to greater pressure and heat than the preliminary coating whereby the conductors of the armature are protected from the destructive effect of the necessarily high pressure required to successfully apply the second 30 coating.

In carrying the invention into effect the laminæ constituting the core of the armature, are coated with a condensation product, such as liquid condensite, or bakelite varnish and allowed to dry. They are then assembled and subjected to pressure sufficient to cause adhesion of the adjacent rings or 35 discs to make the core structure self supporting while the conducting wires are placed thereon. The conducting wires, or coils, are coated with similar varnish as they are being applied, or thereafter. When the 40 windings are in place the armature is then preferably enclosed in a mold and subjected to relatively slight pressure, whereby they may be pushed into uniform shape and configuration and while in the mold they are 45 subjected to heat to harden the condensation product about the windings and to cause greater adherence of the core parts. The structure is then removed from the mold and placed in another mold, wherein an armor 50 of condensation product is formed around the armature conductors, entirely covering

or encasing them, and it may also be placed about and between the commutator bars, or sections, to hold the bars in spaced apart relation and to support the commutator upon 60 the core structure.

During the second treatment it is preferably, subjected to a greater pressure and higher temperature than before. The windings are, however, better enabled to withstand the greater pressure and higher temperature because of the prior treatment, by the effect of which the preliminarily hardened phenolic compound protects the wires as the subsequent heating does not soften it. 70 By this method of construction the armature is insulated and the parts are firmly held together by the same adhesive, insulating, relatively refractory medium.

In the drawings 75
Fig. 1 is an elevation of a conventional laminæ of an armature.

Fig. 2 shows a pile of the laminæ, to constitute the core, placed between two pressure applying elements. 80

Fig. 3 is an end view of the armature, without the spider.

Fig. 4 is a section of one of the molds or presses in which the armature is preliminarily placed, for the purpose of reforming the coils and for preliminarily hardening the liquid insulating medium with which they are coated. 85

Fig. 5 is the mold or press in which the armature is placed for the second operation 90 showing the application of the condensation product around the conductors and supporting the commutator by the armature core.

Fig. 6 is a section taken on line 6—6 of 95 Fig. 5.

In all the views the same reference characters are employed to indicate similar parts.

10 represents a conventional armature laminæ having peripheral openings or notches 11 within which the windings 12 are to be contained. The laminæ are placed upon a spider 13 and then subjected to pressure, between two pressure applying elements 14 and 15, which may be a part of a hydraulic press, or the like. In the preliminary operation, each of the laminations is first coated with a phenolic condensation product, such for example as condensite or bakelite varnish, which is allowed to dry, after which they are placed in a pile, as shown in Fig. 2, and subjected to pressure. 100 105 110

The pressure causes adhesiveness between adjacent laminæ sufficient to hold the core structure together so that it becomes a self supporting member of the armature. After 5 the core thus formed has been taken from the mold or press, it is then wound in proper form with conductors that are located within the notches or openings 11 around the periphery of the core. During the winding 10 operation, or immediately thereafter, the conductors, which are usually covered with cotton or silk, are saturated with a phenolic varnish and before the varnish becomes hardened, the wound core is placed in the 15 mold 17, shown in Fig. 4, in which the conductors 12, located at the respective ends of the armature, are re-formed or pressed into uniform shape and configuration, by the relatively light pressure applied to the mold 20 parts and then the armature, while in the mold, is subjected to heat, of a relatively low temperature. This is accomplished while the armature windings are plastic or pliable and the wires constituting the same 25 may be easily moved or pressed into shape or position and the application of a relatively low temperature does not injure the armature windings but is sufficient to set the cementitious material, or cause it to 30 harden. The armature is then removed from the mold and permitted to cool, after which it is placed in another mold 18 of slightly different configuration, so that an insulating material 19 may be formed around the 35 outside of the coils 12 and at the same time the commutator bars 20 may be properly spaced apart, as shown in Fig. 6, and temporarily held at the end of the armature so that the insulating medium 19 may be 40 molded around the commutator, as at 21, and around the end of the armature, as at 22. The medium 21 is sufficiently strong to hold the commutator in place, supported on the core of the armature and at the same 45 time it serves as an insulation between the adjacent bars. Armature wires 23 are led from the armature coils and connected to the commutator bars 20 by suitable means, as by passing them thru small apertures 24 or in any other desirable way of securing the respective bars to the armature coils.

After the armature has been subjected to greater heat and higher pressure in the mold 18, shown in Fig. 5, for the purpose of placing the armor 19 around the coil, it is 50 then removed from the mold and after being cooled, it is in proper condition for operation.

When the core of the armature is subjected to pressure and heat in the press 14 and 55 15, as shown in Fig. 2, the spider 13 may at the same time be within the core structure so that the application of pressure to the laminæ will have the effect of causing adhesion between the respective laminæ and

the spider, so that the spider will not need any other means of connecting these parts together when the structure is subsequently treated, as in the mold 18 and subjected to the higher temperature, the setting of the 70 cement between the leaves or disks of the laminated structure and between it and the spider, tends to make a very adhesive union between these parts.

In placing the armature structure in the 75 mold 18, the phenolic condensation product may be placed in powdered form in the groove 26 within which the ends of the windings 12 of the armature core are located and furthermore a condensation product 80 may also be placed in and around the upper end of the armature, whereupon the plunger 27, when placed within the body part 28 of the mold and forced into the position shown in Fig. 5 will cause the powdered material to be forced into intimate contact with the parts of the core, around 85 which space in the mold is left for the purpose and the heat will convert it into a hardened homogeneous mass. 90

The mold ring 30 may have any suitable means for the purpose of temporarily holding the commutator bars 20 in spaced relation. The ring 30 may be held in place in the mold after the commutator bars are 95 located thereon in a manner described, by means of screws 29, taking thru the spacing rings 30 into the portion 31 of the mold. The part 31 is held in the position shown, by bolt 32, and a nut 33 that engages the 100 end of the bolt and which passes thru the member 34 of the mold. The parts are assembled in the manner described before the plunger 27 is introduced into the mold and when the armature has been completed, as 105 herein disclosed, the parts of the mold are disassembled and the armature removed therefrom.

While I have herein shown a single embodiment of my invention and a means and 110 method by which it may be carried into effect, it will be manifest to persons skilled in the art that many changes may be made in the general arrangement and configuration of the parts and slight changes in the mode 115 of operation within the scope of the appended claims.

Having described my invention, what I 115 claim is:—

1. Steps in a method for building armatures for dynamo electric machines, which consists in winding conducting wires on a core of an armature and coating the wire with a liquid condensation product; applying pressure and heat to reform the windings while pliant and to harden the condensation product; covering the windings with a coating of condensation product and again subjecting the structure to pressure and heat to harden the covering. 130

2. The method of building armatures for dynamo electric machines, which consists in winding conducting wires on the core of an armature and coating the wires with a phenolic varnish; applying pressure and heat to the windings to shape them while pliant and to harden the varnish; covering the windings with a coating of phenolic product and again subjecting the structure to pressure and heat greater than that primarily applied to harden the covering.

3. Steps in the method of building armatures for dynamo electric machines which consists in winding the conducting wires on the core of an armature and coating the wires with a heat hardening phenolic varnish; applying pressure and heat to the windings while pliant to harden the varnish; spacing commutator segments about the armature; connecting the coils of the windings to the respective segments; covering the windings and parts of the segments with a coating of heat hardening phenolic product and subjecting the structure to pressure and heat greater than that primarily applied to harden the coverings and commutator supports.

4. Steps in the method of building armatures for dynamo electric machines which consists in coating the laminæ of the core with phenolic varnish; stacking the laminæ and applying pressure sufficient to make the core self-supporting; winding the core with conductor coils; varnishing the conductors; applying heat to the core and windings while the latter are pliant to harden the varnish and to increase its adhesiveness; covering the hardened windings with a condensation product; applying pressure and again applying heat to the structure to complete the reaction of said product to harden it.

In testimony whereof I hereunto subscribe my name.

VINCENT G. APPLE.
